TEN COMMANDMENT LAMP BASE

Sara Rae Naimon, Milwaukee, Wis.

Application February 27, 1956, Serial No. 40,381

Term of patent 14 years

(Cl. D48—20)

Fig. 1.

Fig. 2.

I claim:
The ornamental design for a ten commandment lamp base, as shown.
